UNITED STATES PATENT OFFICE.

JOHN D. HENSON, OF LAKEVIEW, OHIO.

CURTAIN-FIXTURE SUPPORT.

No. 806,141.

Specification of Letters Patent.

Patented Dec. 5, 1905.

Application filed March 23, 1905. Serial No. 251,682.

To all whom it may concern:

Be it known that I, JOHN D. HENSON, a citizen of the United States, residing at Lakeview, in the county of Logan and State of Ohio, have invented a new and useful Curtain-Fixture Support, of which the following is a specification.

This invention relates to means for supporting window-shade rollers and curtain-
10 poles.

The principal object is to provide a simple article of manufacture which can be formed from a single piece of metal, is readily applicable to a window-frame, and when placed thereon is strong and rigidly braced to properly support the shade-roller and curtain-pole, and is not liable to become misshapen or deranged from the weight thereon and strains applied thereto.

20 The preferred embodiment of the invention is illustrated in the accompanying drawings, wherein—

Figure 1 is a perspective view of a portion of a window-frame, showing the improved fixture-supports applied thereto. Fig. 2 is a detail perspective view of one of said supports.

Similar reference-numerals designate corresponding parts in both figures of the drawings.

30 The embodiment illustrated in the accompanying drawings is formed from a single piece of round wire; but it will be evident that the structure can be made of metal strips or cast or stamped. The device, however, as an article of manufacture consists of an upper threaded terminal shank 3, formed at its outer end into an open shade-roller-supporting bracket 4, the portion connected to the outer end of the shank being downwardly 40 looped into a hook 5, forming a seat 6 for the reception of a gudgeon of the roller. The other end of the wire is offset and formed into an eye 7, adapted to receive a fastening-screw 8, and the portion connected to this eye is 45 bent into a curtain-pole-supporting bracket 9, formed by doubling the wire upon itself, as shown at 10, and curving said doubled portion to form a pole-receiving seat 11.

An integral connection between the brackets 4 and 9 is in the form of a rearwardly-extending loop, one arm 12 of said loop constituting the upper arm of the pole-holding bracket, the other arm 13 of said loop constituting the lower arm of the wire-holding bracket. This loop is thus located between

the brackets, and its rear end 14 is disposed between the fastening-terminals 3 and 7, constituting an abutment adapted to engage the window-frame, as illustrated in Fig. 1.

In applying the device the shanks 3 are 60 first screwed into the window-frame by turning the fixtures until the loops 14 abut against said frame. Thereupon the fastening-screws 8 are passed through the eyes 7, consequently securing the fixtures in place. It will be evi- 65 dent that these devices can be cheaply manufactured, that they constitute rigid supports for both curtain-poles and shade-rollers, and that being braced between the terminal fastening devices they are not liable to become 70 deranged from the weight of the articles supported therefrom.

From the foregoing it is thought that the construction, operation, and many advantages of the herein-described invention will 75 be apparent to those skilled in the art without further description, and it will be understood that various changes in the size, shape, proportion, and minor details of construction may be resorted to without departing from 80 the spirit or sacrificing any of the advantages of the invention.

Having thus described my invention, what I claim as new, and desire to secure by Letters Patent, is—

85 1. As an article of manufacture, a single-piece curtain-fixture having an outstanding roller-supporting bracket and an outstanding pole-supporting bracket, said brackets being located one above the other and spaced from 90 each other, an integral rearwardly-extending threaded fastening-terminal shank carried by the outer end of one of the brackets, the outer end of the other bracket having an eye to receive a fastener, and a rearwardly-ex- 95 tending integral connection between the brackets located between the threaded shank and the eye and spaced therefrom, said connection separating the brackets and furthermore constituting an abutment that engages 100 a window-frame.

2. As an article of manufacture, a curtain-fixture support formed from a single wire and comprising an upper threaded fastening-terminal, said wire adjacent to the threaded 105 terminal being bent into a roller-supporting bracket, an eye formed at the lower end of the wire for the reception of a fastening device, the wire adjacent to said eye being bent into a pole-holding bracket, and an integral 110

rearwardly-looped connecting portion between the roller-supporting bracket and the pole-bracket, the rear portion of said loop abutting against the window-frame between 5 the fastenings and constituting an intermediate brace for the fixture.

In testimony that I claim the foregoing as

my own I have hereto affixed my signature in the presence of two witnesses.

JOHN D. HENSON.
